TERMINAL FOR ELECTRIC CABLES

Charles L. Marks, Pittsfield, Mass., assignor to
General Electric Company, a corporation of
New York

Application August 26, 1937, Serial No. 161,051

4 Claims. (Cl. 173—353)

The present invention relates to terminals and especially for high tension electric cables. Such terminals commonly comprise a fixed metal base to which the sheath of the cable is secured and upon which is mounted a vertically disposed chambered insulator. The insulator is provided with a metal cap in which is mounted a terminal stud for conveying current from the conductor of the cable to an external line or other conductor. To ensure good electrical connection between the conductor and stud flexible connectors are employed to unite them. Because the conductor and insulator have unequal expansions and contractions for the same change of temperature, the flexible connectors may be and sometimes are subjected to such strains as to injure them.

The object of my invention is the provision of an improved cable terminal in which the insulator and the flexible connectors are protected at all times from injurious strains.

For a consideration of what I believe to be novel and my invention, attention is directed to the accompanying description and the claims appended thereto.

In the accompanying drawing which is illustrative of my invention, Fig. 1 is a view partly in elevation and partly in section of a cable terminal; Fig. 2 is a sectional view of the upper part of the terminal, and Fig. 3 is a plan view of a split supporting ring.

4 indicates the lead sheath of a cable which is secured to the lower end of the metal base part or housing 5 of the terminal as by means of a wipe soldered joint 6, for example. The cable may extend downwardly several feet in a more or less vertical direction depending upon the location of the terminal. The upper end of the housing has a flange 7 which is supported from the under side as by parts 8, for example. On top of the flange is a flanged metal ring 9 in which the lower end of the chambered insulator 10 is supported and sealed. As illustrated, the insulator is made of porcelain with numerous parallel ribs to increase the creepage surface but it may be made of other insulating material. Mounted on top of the insulator and secured thereto in any suitable way is a cap or cover 11, and between it and the insulator is a packing 12 to ensure a fluid-tight connection. The chamber 13 of the insulator when the cable is in service is filled with suitable insulating liquid, such as degassed oil for example.

Supported by the cap is a hollow screw threaded terminal stud 14 having an enlarged

head 15 located on the under side of the cap, said stud being firmly secured in place by the external nut 16. Between the upper surface of the head and the under surface of the cap is a fluid-tight packing 17. On the upper end of the stud is a pair of nuts 18 for uniting it with a line or other conductor. The outer end of the hollow stud is closed by a screw plug 19.

The sheath is removed from that portion of the cable within the insulator. 20 indicates the conductor of the cable and in the present illustration has a hollow core 21 which is filled with degassed oil at super-atmospheric pressure. Surrounding the conductor is factory applied insulation 22. The conductor with the insulation removed from the end thereof is located in a socketed head 23 and is united therewith, as by solder for example. Above the head is an extension 24 which makes a loose telescopic fit in the bore or hollow lower end of the terminal stud and has a peripheral groove 25, said groove being of a length to permit of the extension moving upwardly within the bore of the stud when the expansion of the conductor is greater than that of the insulator. Located in the groove is a split ring 26 which supports a portion of the weight of the conductor when it is in the normal position, as shown. The split ring is held against axial movement by an internally threaded shouldered nut 27, the threads of which engage corresponding threads on the lower end of the terminal stud. Due to the axial length of the groove 25 the conductor and head 23 can move upwardly from the normal or cold position shown due to unequal heating of the parts but cannot move downwardly from said position. In order to establish and maintain good electrical connection between the relatively movable parts, one or more flexible connectors 28 are provided of which two are shown in the sectional drawing. Each connector has a head 29 at each end which ends are soldered or otherwise secured to the terminal stud and to the head 23. The connectors are somewhat longer than the distance between points of attachment so that at no time are they under longitudinal strains tending to break them or to injure the points of connection.

In the extension 24 of the socketed head is a passage 30 communicating with the hollow core or channel of the cable and terminating at its upper end in a valve seat that cooperates with the valve 31 located at the bottom end of a rod 32 which extends upwardly into the terminal stud. The rod has a screw thread at its lower end which engages internal threads in the extension 24. Be- 55

tween the valve and seat is a lateral port 33 for establishing communication between the cable core and the chamber 13 of the insulator. By removing the screw plug 19 at the top of the 5 terminal stud and inserting a suitable tool to engage the rod 32, the valve may be moved to close the valve seat at the upper end of the passage 30 or to open it as shown, after which the plug is replaced. The valve 31 and lateral port 33 are 10 used during the installation of the terminal. While the chamber of the insulator is being evacuated and filled with insulating fluid, such as degasified oil, the valve would be closed. After the filling operation is completed, the valve is 15 opened and communication established between the core of the cable and the chamber of the insulator. The plug 19 is normally in place as shown.

From the foregoing, it will be seen that any 20 weight or pull of the conductor at normal temperature is sustained by the split ring 26 and associated parts, and for that reason no strains are imposed on the flexible connectors 28. On the other hand, it will be seen that when the 25 conductor expands at a greater rate than the insulator, it can freely move upwardly and that the only effect on the flexible connectors will be to bow them outwardly by a slightly greater amount. The sheath 4 of the cable is secured 30 to the lower part of the casing or housing 5 and therefore remains in its fixed position but this does not affect the conductor and its insulation because they are capable of a limited axial movement within the sheath and independ- 35 ently thereof.

Due to the telescopic relation of the stud and the extension 24 as described, the expansion of the conductor will not subject the insulator through the cap to upward pushing effects which 40 otherwise might result in cracking it. Such an accident would necessitate a new insulator accompanied by an expensive repair job. The upper end of the extension 24 being smaller in diameter than the opening or bore in the stud will compensate for any small inaccuracies in alignment of the conductor within the insulator, and the connectors 28 being flexible will likewise compensate for such misalignment. It is to be observed in this connection that the conductor is 45 relatively stiff and unyielding and that the porcelain insulator is practically a rigid body securely fastened at its lower end. Stated briefly, my improved construction results in a terminal free of internal injurious strains due to unequal expansion and contraction of the parts and of 50 trouble due to small misalignment of the parts.

What I claim as new and desire to secure by Letters Patent of the United States, is:

1. A terminal for an electric cable comprising 60 a chambered insulator, a support for the bottom end thereof, a cap for closing the top of the insulator, a terminal stud mounted on and extending outwardly through the cap, the stud having a bore at its lower end, a conductor within the insulator extending longitudinally thereof, a head firmly secured to the conductor having an extension at its upper end located within the bore on the stud in movable telescopic relation therewith, a supporting member secured to the lower end of the terminal stud, a means engaging 65 the head and through which it extends located between the extension on the head and the member for limiting the downward move-

ment of the head and conductor but permitting them to move upwardly due to expansion of the conductor, and a flexible connector secured at one end to the terminal stud and at the other end to the head for electrically connecting them, the connector being protected by the means from undue strains due to downward movement of the 5 cable.

2. A terminal for an electric cable comprising 10 a chambered insulator, a support for the insulator located at its bottom end, a cap for the top of the insulator, a terminal stud mounted on and extending through the cap, said stud having a head located under the cap containing a central bore, a cable having its sheath connected 15 in fixed relation to the support of the insulator and its conductor extending longitudinally of the insulator, a head secured to the conductor, said head having an extension with a peripheral groove, a ring located in and engaging a wall 20 of the groove for limiting downward movement of the conductor and its head but permitting upward unrestrained movement thereof, a means carried by the stud for holding the ring against downward movement, and a flexible connector 25 electrically uniting the stud and the conductor head, the ring and means protecting the flexible connector from undue strains due to a downward movement of the cable.

3. A terminal for an electric cable comprising 30 a chambered insulator, a support for the insulator located at its bottom end, a cap for the top of the insulator, a terminal stud mounted on and extending through the cap, said stud having an externally threaded head located under 35 the cap containing a central bore, a cable having its sheath connected to the support of the insulator and its conductor extending longitudinally of the insulator, a head secured to the conductor, said head having a peripheral groove 40 and being arranged in telescopic relation with the bore of the stud, a split ring located in the groove and of less axial length than said groove, a nut carried by the threaded end of the stud 45 for holding the ring against its lower end, and a flexible connector secured at its ends to the stud and head for electrically uniting them, the ring and nut serving to protect the connector from undue strains due to a downward movement 50 of the cable.

4. A terminal for an electric cable comprising 55 a chambered insulator, a support for the insulator located at its bottom end, a metal cap for closing the top of the insulator, a terminal stud having an enlarged head located under the cap within the insulator and also a part extending through the cap, the head having a central bore and a screw threaded lower end, a cable within the insulator extending axially thereof, a head secured to the cable having an extension located 60 within the bore of the stud in movable telescopic relation therewith, a means engaging the extension for limiting the downward movement of the cable, a nut threaded to the lower end of the head of the stud for supporting the means, and bowed flexible connectors secured to the head of the stud at their upper ends and to the head on the cable at their lower ends and enclosing the nut, the means and nut limiting the downward movement of the cable to an amount less than 65 the slack in the connectors.
